(57) **CLAIM**

I claim the ornamental design for an emergency contact fob for a keychain, as shown and described.

DESCRIPTION

FIG. 1 is a front view of the emergency contact fob for a keychain.

FIG. 2 is a rear view of the claimed design.

FIG. 3 is a top view of the claimed design.

FIG. 4 is a bottom view of the claimed design.

FIG. 5 is a right side view of the claimed design.

FIG. 6 is a left side view of the claimed design; and,

FIG. 7 is a perspective view of the claimed design.

The broken lines show portions of the article that form no part of the claimed design.
